UNITED STATES PATENT OFFICE.

LUDVIG T. PETERSEN, OF YOUNGSTOWN, OHIO.

METHOD OF MANUFACTURING RESILIENT ARTICLES.

1,115,240.

Specification of Letters Patent. Patented Oct. 27, 1914.

Application filed May 25, 1914. Serial No. 840,929.

To all whom it may concern:

Be it known that I, LUDVIG T. PETERSEN, a citizen of the United States, residing at Youngstown, in the county of Mahoning 5 and State of Ohio, have invented certain new and useful Improvements in Methods of Manufacturing Resilient Articles; and I do hereby declare the following to be a full, clear, and exact description of the invention, such as will enable others skilled in the art to which it appertains to make and use the same.

My present invention relates to methods of manufacturing resilient articles, including balls especially such as used in playing the game of golf, or similar games, wherein it is important that the ball used should possess among other characteristics that of durability, a high degree of resiliency, true 20 spherical form, uniformity and compactness of structure, a center of gravity coincident with its center of symmetry, and a constant radial expansive strain upon the interior of its outer cover. They should also possess 25 among other qualifications that of withstanding the blows to which they are continually subjected with varying degree of force, administered by driving implements such as golf clubs; when fairly struck they 30 should respond actively by reason of their inherent elasticity, and should fly with accuracy and precision because of their ballistic properties; they should be provided with a tough resilient outer casing or cover capable 35 of restraining expansive pressure inherent in the body of the ball, but not likely to be disrupted or damaged in use; they should be capable of instantly recovering their normal spherical form after momentary distortion 40 by a blow, or by forcible contact with an unyielding object of any description; and should be proof against permanent distortion under the most severe tests and usage to which such balls are ordinarily subjected.

45 The present method has for an object the production of resilient articles, particularly golf balls, possessing all of the characteristics and qualifications above enumerated.

50 A further object is the production of coreless balls from windings or superimposed layers pieces or strips of material which in the process of manufacture are rendered both plastic and elastic and are finally shaped in heated molds under pressure.

55 A further object is the production of balls

of uniform compactness and density, practically free from entrapped air bubbles, and having a marked degree of resiliency in contradistinction to solid balls which are proverbially dead.

60 A further object is that of inclosing the body of resilient balls within a tough, durable and relatively thin, seamless outer casing, absolutely without joints or welding, and consequently without the liability 65 of breakage which attends covers made in two or more sections.

A further object is the formation of balls under pressure in suitable hot molds, and allowing them to cool without removal, 70 thereby permitting heat of the molds to penetrate the entire mass thus automatically adjusting its balance, and subjecting the center of the ball to a cumulative pressure effect the extent of which is varied accord- 75 ing to the depth of heat penetration.

A further object is the formation of a ball-body from balata or its equivalent impregnated with particles of cured rubber, a ball-cover from refined balata, gutta percha, 80 or one of its substitutes, or like material which may or may not be similarly impregnated, and then uniting said body and cover by molding them into one homogeneous mass.

85 A further object is to simplify the operation of making golf balls, and to reduce the cost thereof; and still further objects will hereafter be apparent to persons skilled in the art.

90 The invention will be hereinafter described and pointed out in the claims following.

In the accompanying drawings which 95 form part of this application for Letters Patent, corresponding numerals of reference designate like parts in the several views.

Figure 1 represents diagrammatically, a 100 fragment of a sheet of balata or other substance having like physical properties. Fig. 2 is a strip of like material cut transversely from the sheet shown by Fig. 1. Fig. 3 is a strip such as shown by Fig. 2, partially stretched across its grain. Fig. 4 105 is a view in perspective showing the body of a golf ball in the process of winding or plying. Fig. 5 is a side elevation of a completely formed ball-body upon a hot-plate including a crude exemplification of heat- 110

ing means. Fig. 6 is a central vertical section of the ball-body shown by Fig. 5, with its surrounding seamless cover, both somewhat oversize, and contained within a mold 5 preparatory to final shaping, and, Fig. 7 is a side elevation of a completed ball shown partly in section.

For purposes of the following description the material employed as a basis will be referred to as balata, but it should be understood at the outset that my present invention is broad enough to include any substance, or gums, having like physical properties, such for example, as gums of the 10 gutta group generally. And furthermore, it should be understood that variations of the exact method steps and the stated order thereof, may be made and substituted for those hereinafter set forth and still be 15 within the scope of my invention.

Reference being had to the drawings and numerals thereon, 1 represents a sheet of balata, made from balata gum which has been previously softened in hot water, 20 washed, and sheeted by milling between heated rolls in the usual and well understood manner. These sheets 1 are ordinarily rolled out to a length of one hundred, or one hundred and fifty feet, and a width of 25 from two to three feet, more or less, but in any event the kneading or calendering operation invariably produces a grain, such as diagrammatically shown at 2, running longitudinally of the sheet.

30 In carrying out my invention a sheet of balata such as 1, while in the course of kneading or calendering, is thoroughly impregnated with a multiplicity of individual particles of cured rubber 3, varying in size and weight according to the character of balls to be produced. It is characteristic of balata to stretch in one direction and not in the other. 35 that it is say, it is capable of being readily stretched in a direction at right angles to its grain, but is practically non-stretchable with the grain, and when stretched remains stretched until contracted by the application of heat. Utilizing this physical characteristic a strip, strips, or pieces 4 of suitable width, are first cut from said sheet 1 transversely across the grain 2 thereof, and are each drawn out, or stretched to their elastic limit, by hand or otherwise, as indicated at 5 in Fig. 3 of the drawings there- 40 by rendering latent the contractile qualities of the material, this preliminary stretching being effected cold, or at a normal temperature of from sixty to eighty degrees Fahrenheit, more or less. A small nucleus 6 is thereupon rolled into one end of the first strip 4, and upon this as a center are successively plied or overwound, in superimposed relation, and without further stretching a succession of such strips 4, each prelimi- 45 narily stretched to render latent its con-

tractile qualities, and cumulatively applied until approximately the desired size and spherical form of a ball-body has been produced. This accomplished, the ball-body, such as shown by Fig. 5, is subjected to a 70 mild degree of heat, by any approved heat-producing means, whereby the latent contractile qualities inherent in the previously stretched strips 4 are stimulated or restored, causing a cumulative radial internal pressure and rendering the ball as a whole peculiarly resilient and responsive in long drives, and yet comparatively dead to light blows as in putting. This restoration of the contractile properties of balata is 75 essential to the production of superior balls, but it is by no means necessary that it shall take place at the time and stage of manufacture above indicated, on the contrary the heating is equally effective, and in some instances more so, when applied at frequent intervals during the formation or winding of the ball-body. Obviously, the heat-producing means aforesaid may be varied indefinitely without departing from the spirit 80 of this invention, or the method step which it involves, but in the present illustrations a hot plate 7 is shown, heated by gas jets 8 for example, because such plate in addition to heating facilitates a preliminary 85 shaping of the ball by rolling same upon the plate during the process of manufacture, either under the hand of an operator, or under a second superimposed non-yielding plate, (not shown) either heated or un- 90 heated. The ball-body is now ready to receive its outer cover or casing 9, which by preference is plied up as aforesaid, either of strips 4 impregnated with particles of 95 cured rubber 3, or without the addition 100 of such particles, but preferably without them. This cover 9, unlike most balls which are designed and intended for use in the game of golf, is a seamless and jointless 105 envelop or casing, made oversize from overwound strips 4 of balata applied in the manner hereinbefore described, and treated as 110 set forth in connection with the building of the ball-body, except that refined balata, gutta-percha, celluloid or like material is 115 employed. The entire ball-body and overwound restraining cover 9, while still somewhat plastic, are next placed in heated molds 10 and subjected to pressure, which 120 not only insures a true spherical form, but causes the ball to automatically adjust its center of gravity to correspond precisely with its center of symmetry, and produces a suitable surface configuration such as the 125 well known "bramble" design which in the present drawings is used merely as an example. In this condition the ball is permitted to cool slowly, and its cover to set, before removal from the molds. After cooling the completely formed ball is removed from 130

the mold press and coated in the usual manner with white paint, celluloid varnish, or any of the usual coatings, care being taken to select a coating material the vehicle of which has an adhesive or solvent affinity for the material of which the ball cover is made. Acetone is a solvent for some of the constituents of balata, so that any paint or varnish containing acetone will answer for a balata cover, or for covers made of a material which is a substitute for balata.

From the foregoing it will be seen that covers 9 made and applied in accordance with the present method may be comparatively thin, and consequently more resilient than the thick covers used in rubber-wound balls, or in various makes of balls containing acids or gases for the purpose of exerting pressure upon the ball covers, sometimes causing the latter to break under the impact of a blow with possible disastrous results to persons handling them. And it will be noted with what facility balls made under the present process may be reheated, reformed, resurfaced, and repaired, if in the course of long service their outer surfaces should become worn or otherwise injured. It will also be noted that the strip, strips or pieces of stretched balata 4 employed in the production of balls under and in accordance with the present method, may vary in width and thickness greatly from a mere thread to practically any desired width or thickness, and, indeed, it is within the scope of this invention to construct balls from a single sheet of balata stretched, formed, heated and finally shaped while semi-plastic by agency of heated molds. It will also be noted that I do not herein claim the ball, made according to my improved method as an article of manufacture, for the reason that such claims are made in a separate application filed by me in the United States Patent Office simultaneously herewith.

Having thus described my improved method what I now claim is:

1. The method of manufacturing resilient articles from material possessing latent contractility, involving the following method steps, namely, forming the article into the desired shape, and stimulating the latent contractile qualities of the material.

2. The method of manufacturing resilient articles from material possessing latent contractility, involving the following method steps, namely, forming the article into the desired shape, and stimulating the latent contractile qualities of the material by the action of heat.

3. The method of manufacturing resilient articles from material possessing latent contractility, involving the following method steps, namely, impregnating the material with particles of cured rubber,

forming the article into the desired shape, and stimulating the contractile qualities of the material.

4. The method of manufacturing resilient articles from material possessing contractile qualities, involving the following method steps, namely, impregnating the material with particles of cured rubber, rendering latent said contractile qualities, forming the article into the desired shape, and stimulating the contractile qualities of the material.

5. The method of manufacturing resilient articles from gum possessing contractile qualities, involving the following method steps, namely, impregnating the gum with particles of cured rubber, stretching the gum to render latent the contractile qualities, forming the article into the desired shape, and stimulating the contractile qualities of the gum.

6. The method of manufacturing resilient articles from gums of the gutta group possessing contractile qualities, involving the following method steps, namely, impregnating the gum with particles of cured rubber, stretching the gum to render latent its contractile qualities, forming the article into the desired shape, and stimulating the contractile qualities of the gum by the action of heat.

7. The method of manufacturing resilient articles from balata, involving the following method steps, namely, impregnating the balata with particles of cured rubber, stretching the balata to render latent its contractile qualities, forming the article into the desired shape, and finally stimulating the contractile qualities of the balata.

8. The method of manufacturing resilient articles from strips of balata impregnated with particles of cured rubber, involving the following method steps, namely, stretching said strips to render latent their contractile qualities, forming them into the desired shape, and stimulating the contractile qualities of said strips by the action of heat.

9. The method of manufacturing resilient articles from sheeted balata, involving the following method steps, namely, impregnating the balata with particles of cured rubber, cutting the balata into strips, stretching said strips to render latent their contractile qualities, over-winding said strips to form a ball, and stimulating the contractile qualities of the strips after winding by the action of heat.

10. The method of manufacturing resilient balls from balata, involving the following method steps, namely, impregnating the balata with particles of cured rubber, cutting the balata into strips, stretching said strips to render latent their contractile qualities, overwinding said strips into the form of a ball, stimulating the contractile

qualities of the strips after winding by the action of heat, and compressing the ball while warm to final size.

11. The method of manufacturing resili-
ent balls from balata, involving the follow-
ing method steps, namely, impregnating the
balata with particles of cured rubber,
stretching the material to render latent its
contractile qualities, shaping the material
into the form of a ball, stimulating the con-
tractile qualities of the material by the
action of heat, and finally molding the ball
under pressure in molds.

12. The method of manufacturing resili-
ent balls from balata, involving the follow-
ing method steps, namely, impregnating the
balata with particles of cured rubber,
stretching the material to render latent its
contractile qualities, shaping the material
into the form of a ball, stimulating the con-
tractile qualities of the material by the ac-
tion of heat, and finally shaping the ball
under pressure in hot molds allowing it to
cool while still contained within the molds.

13. The method of manufacturing resili-
ent balls from strips of balata impregnated

with particles of cured rubber, involving the
following method steps, namely, stretching
said strips to render latent their con-
tractile qualities, winding said strips into
the form of a ball, heating said strips after
winding to restore their contractile qual-
ties, and finally applying an outer resilient
cover to the ball.

14. The method of manufacturing resili-
ent balls from strips of balata impregnated
with particles of cured rubber, involving
the following method steps, namely, stretch-
ing said strips to render latent their con-
tractile qualities, overwinding said strips
upon themselves to form a ball-body, heat-
ing said strips after winding to restore their
contractile qualities, applying an outer elas-
tic cover, and finally molding said ball-body
and cover into a homogeneous sphere.

In testimony whereof I affix my signature,
in presence of two subscribing witnesses.
